Fig. 3.

Fig. 4.

FIG. 1 is a side elevational view of an air tank;
FIG. 2 is a top plan view;

FIG. 3 is a top perspective view; and
FIG. 4 is a bottom perspective view.

This is a continuation of design application, Ser. No. D. 85,727, filed June 14, 1965, now abandoned.

The dominant features reside in the solid line portions and are further characterized by the diminishing circular shaped cover portion having a symmetrical handle disposed medially thereof in combination with a recessed circular outer bottom support ring and a concave bottom surface.

I claim:

The ornamental design for an air tank, substantially as shown and described.
